[57] CLAIM

The ornamental design for a golf club putter head, as shown and described.

DESCRIPTION

FIG. 1 is a rear top perspective view of a golf club putter head showing my new design.

FIG. 2 is an end elevation view thereof;

FIG. 3 is an end elevation view thereof;

FIG. 4 is a frontal top perspective;

FIG. 5 is a frontal elevation view thereof;

FIG. 6 is an enlarged frontal elevational view of a second embodiment of the golf club putter head as disclosed in FIG. 1;

FIG. 7 is an end elevational view of FIG. 6;

FIG. 8 is a rear elevational view of FIG. 6; and,

FIG. 9 is an opposite end elevational view of FIG. 7.

The undisclosed portions of the second embodiment are identical to those disclosed in the first embodiment.
